UNITED STATES PATENT OFFICE.

SIEGFRIED ROSENZWEIG, OF YORK, PENNSYLVANIA.

LUBRICATING DEVICE FOR STEAM-ENGINE VALVES.

1,125,725.

Specification of Letters Patent.

Patented Jan. 19, 1915.

Application filed August 1, 1914. Serial No. 854,555.

To all whom it may concern:

Be it known that I, SIEGFRIED ROSENZWEIG, a citizen of the German Empire, residing at York, in the county of York and State of Pennsylvania, have invented a new and useful Improvement in Lubricating Devices for Steam-Engine Valves, of which the following is a specification.

My improvement has to do more particularly with steam valves of the puppet type, and its object is to effect thorough and effective lubrication of the parts as well as to supply the requisite quantity of lubricant to the entering steam as it passes through the steam chest to the steam cylinder. To this end the lubricant is fed into the tubular guide in the steam chest which receives and supports the valve spindle, and is caused to pass along between the spindle and guide until it reaches the valve, through apertures in the head of which it is discharged and permitted to escape into the steam chest, to there meet and mingle with the live steam. It is this feature which mainly characterizes my improvement.

In the accompanying drawings, to which I shall now refer for a better understanding of my improvement—Figure 1 is a vertical axial section of so much of a steam chest, valve and engine cylinder as needed for purposes of explanation. Fig. 2 is a like sectional view, on enlarged scale, of so much of the valve, and its supporting guide, as needed to fully illustrate the lubricating devices.

A is the steam cylinder; B is the steam chest, cast in one, as usual, with the steam cylinder; and C is the steam inlet valve with its spindle C' supported in a central tubular guide D in the steam chest, in which it can reciprocate to cause the valve C to move from or seat itself upon the annular valve seats b, b', with which the steam chest is provided.

The port or entrance into the steam cylinder is indicated at a; and c is the clearance chamber between said port a and the valve. There will be one of these valves at each end of the steam cylinder, as usual in engines of this character. The valve may be operated by any suitable gear, preferably by valve gear such as set forth in my Patent No. 1,059,567 of April 22, 1913.

I come now to those parts of the structure in which my invention is found.

E is a pipe leading from any suitable

source of supply of the lubricant under suitable pressure, connected with and discharging into the duct or passage e in the rear wall b³ of the valve chest, which leads the lubricant into a shallow chamber e' in the guide D surrounding the valve spindle C'. The contacting surfaces of the valve spindle C and the guide D, between the chamber e' and the valve are suitably formed to cause the lubricant to pass from the chamber e' between them to the head of the valve, this result is attained in the present instance by means of a spiral peripheral groove f in the spindle. This groove terminates in a shallow chamber g between the front end of the guide and the base or inner end of the head h of the valve; and in the head are formed apertures i—in any suitable number, four in the present instance—extending through it from the chamber g to the front of the valve, through which apertures the oil, which gathers in the chamber g after it has passed between and lubricated the meeting surfaces of the valve spindle and its guide, will pass into the steam space in the steam chest to there meet and mingle with the entering steam. The head h of the valve in this instance forms the front end of a cylindrical hub H which fits and is adapted to slide or reciprocate upon the exterior of the front portion of the guide D, the hub and rim of the valve being connected by spider arms H' (Fig. 2) cast in one with the hub and rim:

In order to lubricate the meeting surfaces of the guide and hub H, suitable feed devices leading from the chamber g may be provided, consisting in the present instance of a feed groove k in the periphery of that portion of the guide encircled by the hub H, said groove communicating with the chamber g and leading lubricant therefrom to and between the meeting faces of the hub and guide, the lubricant, after passing back beyond the hub, discharging into the clearance chamber to there meet and mingle with the steam. Thus the lubricant which is supplied to the steam chest, first of all lubricates the valve spindle (and hub, when one is used), and it is only after having done that work that it enters the steam space to there meet and be taken up by the steam. In this way thorough and efficient lubrication is effected.

Suitable means are provided for prevent-

ing undue escape of the lubricant from the rear of the guide D, there being provided for this purpose in the present instance in the spindle what is known as labyrinth 5 packing, indicated diagrammatically at L.

The invention hereinafter described is applicable to the exhaust valve as well as to the steam inlet valve, and I desire to be understood as including any such obvious 10 modification in my claims.

Having described my improvement and the best way now known to me of carrying the same into practical effect, I state in conclusion that I do not limit myself strictly 15 to the structural details hereinbefore shown and set forth in illustration of my invention, since manifestly the same can be varied to some extent and in some particulars without departure from the spirit of the invention; but 20

What I here claim as new and desire to secure by Letters Patent is as follows:

1. The combination with the steam chest, the tubular guide therein, and a lubricant 25 or oil feed conduit leading from a force feed source and communicating with the interior of said guide, of the valve; the valve spindle carrying said valve and mounted and movable in, and supported by, said guide; feed 30 channels between the meeting faces of the guide and valve spindle through which the lubricant supplied to the interior of the guide is caused to pass forward toward the head of the valve; and discharge ducts in 35 the valve head through which the lubricant passing beyond the feed channels between the guide and the valve spindle is ejected into the steam chest to there meet and min-

gle with the live steam entering said steam chest.

2. The combination with the steam chest, the tubular guide therein, and a lubricant or oil feed conduit communicating with the interior of said guide, of the valve spindle mounted and movable in, and supported by, 45 said guide; the valve carried by and moving with said spindle, and provided with a tubular hub which encircles and fits around the front portion of the guide and moves with the valve; feed channels between the 50 meeting faces of the guide and valve spindle through which the lubricant supplied to the interior of the guide is caused to pass forward toward the head of the valve; a chamber in rear of the head into which the 55 lubricant as it passes beyond the meeting faces of the guide and the valve spindle is received; discharge ducts in the valve head through which a portion of the lubricant which gathers in said chamber is permitted 60 to escape into the steam chest; and feed channels between the meeting faces of the valve hub and guide, also communicating with said chamber, through which another portion of the lubricant which gathers in 65 said chamber is carried back between and caused to lubricate the meeting faces of the hub and guide, and then, after passing back beyond said hub, to escape into the steam chest.

In testimony whereof I affix my signature in presence of two witnesses.

SIEGFRIED ROSENZWEIG.
